United States Patent Office

Des. 190,466
Patented June 6, 1961

190,466

PAPER CAP

John Howard King and George G. King, both of Lexington, Ky.

Filed July 23, 1959, Ser. No. 56,899

Term of patent 14 years

(Cl. D3—13)

FIG. 1

FIG. 2

FIG. 3

FIG. 4

FIG. 5

We claim:

The ornamental design for a paper cap, as shown and described.
